US0D1065003S

(12) **United States Design Patent** (10) **Patent No.:** **US D1,065,003 S**
(45) **Date of Patent:** **** Mar. 4, 2025**

(54) **WHEEL CHOCK**

(71) Applicant: **Motis Brands, Inc.**, Germantown, WI (US)

(72) Inventors: **Robert Krolski**, Kewaskum, WI (US); **Richard Beilstein**, West Bend, WI (US)

(73) Assignee: **Motis, LLC**, Germantown, WI (US)

(**) Term: **15 Years**

(21) Appl. No.: **29/873,553**

(22) Filed: **Apr. 3, 2023**

Related U.S. Application Data

(62) Division of application No. 29/701,014, filed on Aug. 7, 2019, now Pat. No. Des. 987,541.

(57) **CLAIM**

The ornamental design for a wheel chock as shown and described.

DESCRIPTION

FIG. 1 is a perspective view of a wheel chock;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines showing of various portions and other elements in the Figures are for the purpose of illustrating unclaimed portions and form no part of the claimed design.

1 Claim, 5 Drawing Sheets
